UNITED STATES PATENT OFFICE.

JOSEPH L. HEMP, OF ST. LOUIS, MISSOURI.

STOVEPIPE.

1,313,633.

Specification of Letters Patent.

Patented Aug. 19, 1919.

Application filed May 17, 1915. Serial No. 28,620.

To all whom it may concern:

Be it known that I, JOSEPH L. HEMP, a citizen of the United States, and resident of St. Louis, Missouri, have invented certain new and useful Improvements in Stovopipes, of which the following is a specification containing a full, clear, and exact description, reference being had to the accompanying drawings, forming a part hereof.

10 My invention relates to improvements in stove pipes, and the object of my invention is to construct a simple, inexpensive and easily operated stove pipe seam, which may be locked without the employment of extraneous means.

15 With the above object in view, my invention consists in certain details of construction and arrangement of parts hereinafter fully described, pointed out in my claims and 20 illustrated by the accompanying drawings, in which—

Figure 1 is an elevation, with a part removed, of a stove pipe section constructed according to my invention;

25 Fig. 2 is a fragmental cross section taken on the line 2—2 of Fig. 1 looking toward the right; and

Fig. 3 is a view similar to Fig. 2, taken on the line 3—3 of Fig. 1 looking toward 30 the right; and Fig. 4 is a detail longitudinal sectional elevation showing the crimped end bent inwardly. Fig. 5 is a perspective view of my stove pipe section illustrating the preliminary method or manner of locking 35 the edges of the stove pipe together, and Fig. 6 is a fragmental perspective of one end of the stove pipe section illustrating the subsequent operation in locking the edges wherein one flanged edge is partially inserted 40 through the notch formed in the opposing edge.

Referring by numerals to the accompanying drawings,

5 designates the stove pipe section formed 45 from a single sheet of metal. Formed on one margin of the sheet there is an outwardly bent flange 6, which extends throughout the stove pipe section, and formed on the opposite edge of the sheet there is an inwardly bent flange 7, said flanges being adapted to be engaged or interhooked, as is common.

The pipe section bears the usual beads 8 near its ends for the purpose of limiting the extent of telescoping of sections of pipe 50 and at the one end the sheet is longitudi-

nally crimped to slightly taper the pipe to facilitate the telescoping.

In the margin of the sheet intersecting the flange 6, between the bead 8 and the end of the sheet which is longitudinally crimped, there is formed a notch 9. The notch 9 answers as a seat for the opposing flanged edge 6 of the stove pipe section, said edge passing diagonally through the notch and the portion 11 beyond the notch lying beneath the opposing flanged edge when the edges of the section have been locked together for use.

At the end of the sheet opposite the longitudinal crimps and notch 9, parallel with and laterally spaced from the flange 6 is a shoulder 10, which is raised to the plane of the overlying portion of the flange to produce an abutment against which the opposite flange bears to prevent sectional relative 75 movements of the flanges.

It will be understood from this showing that along one margin the stove pipe section has an inwardly bent flange 7 of hook formation which extends from one end of the section to the notch 9, said flange terminating at the notch. Beyond the notch a portion of the stove pipe section (as shown by dotted line in Fig. 1) projects when the pipe section is locked beneath the opposing flanged 80 edge of the stove pipe section. The opposing or opposite edge of the stove pipe section is provided with an outwardly bent flange 6 which extends throughout the section, the said flanges 6 and 7 adapted to be hooked together for locking the stove pipe section.

On the end of the stove pipe section opposite to the end in which the notch 9 is formed, I form a shoulder 10, against which the opposing edge of the stove pipe is adapted 85 to abut when the flanges are hooked or placed in the locked position. In order to lock the stove pipe section together, the stove pipe section is twisted until the end of the side carrying the flange 7 passes the shoulder 10, then the flanges are hooked together, one edge of the stove pipe section resting against the shoulder 10 and the edge of the section carrying the flange 6 being 90 inserted over the portion of the pipe beyond the notch 9. When the stove pipe section is twisted, the shoulder 10 bears against the flange 7, the shoulder 10 being inserted over the portion of the pipe beyond the notch 9.

When the stove pipe section has been assembled, one end is prevented from collapsing by means of one edge of the section resting in the notch 9 and the other end is prevented from collapsing by 110

one edge resting against the shoulder 10, thus affording an effective lock for both ends of the stove pipe section. In Fig. 2 I have shown a cross section of the seam or joint when the stove pipe section is locked, illustrating one edge of the section abutting against the shoulder 10, and in Fig. 3 I have shown a cross section of the seam when the section is locked, showing one edge of the stove pipe section lying in the notch 9 and over the portion of the pipe beyond the notch 9.

In Figs. 5 and 6 I have illustrated the method of assembling the section and locking the edges together. The first operation as illustrated in Fig. 5 is to twist the section in helical form and engage the flanges 6 and 7. When this has been done, the opposing flanged edge is passed diagonally through the notch 9 and the opposite end passed behind the shoulder 10. From this construction it will be observed that both ends of the stove pipe section will be prevented from becoming unlocked by compression. In order to pass the opposing flanged edge diagonally through the notch 9, it is preferable to slightly spring inwardly the portion 11. In Fig. 6 I have shown the flanged edge partly inserted through the notch 9.

As shown by Fig. 4, the end margin of the section, next the crimped portion, is bent inwardly as at 10^a to facilitate introducing the crimped end into a second section.

Having thus described my invention, what I claim as new therein and desire to secure by Letters Patent of the United States is:

1. A stove-pipe section, formed from a single piece of sheet-metal and provided along one margin with a continuous and unbroken outwardly bent hook-flange and on one end with an outwardly formed shoulder pressed from the section adjacent to and paralleling the edge of said flange against which the opposing edge is adapted to rest and provided on the opposite margin with an inwardly turned hook-flange of less length than the first mentioned flange and

with a notch cut beyond the edge of the inturned flange, the portion of the pipe section of the end adjacent the notch, being inwardly bent, the margins of the section being fastened together by twisting the section in helical form and engaging the flanges so that the flanged margin of one end may be inserted in the notch and over the inwardly bent portion and the opposite flanged margin may be positioned behind the outwardly formed shoulder whereby the section is assembled for use without any other operation. 60

2. A stove pipe section formed from a single piece of sheet metal provided along one margin with a continuous and unbroken outwardly bent hook shaped flange and on one end with an outwardly formed shoulder 65 adjacent to and parallel with the edge of said flange against which the opposing edge is adapted to rest, and provided on the opposite margin with an inwardly turned hook shaped flange of less length than the first 70 mentioned flange and with a notch in which the opposing edge is adapted to be seated, a portion of the pipe section of the end adjacent the notch being inwardly bent and positioned beneath the opposing flange when the flanges are engaged, the wall of the notch and the inwardly bent portion adjacent said notch preventing the unhooking 75 of the flanges by compression at one end of the pipe section, and the outwardly formed shoulder preventing the unhooking of the flanges by compression at the opposite end of the section, said flanges being capable of being engaged by giving the stove pipe section a helical form so that the end margin 80 of one end of the section may be seated behind the shoulder and one end of the opposite margin may be positioned within the notch. 85

In testimony whereof, I have signed my 90 name to this specification, in presence of two subscribing witnesses.

JOSEPH L. HEMP.
